UNITED STATES PATENT OFFICE.

ROBERT CHRISTOPH FREDERIK VOGEL, OF HAMBURG, GERMANY, ASSIGNOR TO FIRM
OF VOGEL & HALKE, OF HAMBURG, GERMANY.

WEIGHING MACHINE.

Application filed June 4, 1928, Serial No. 282,758, and in Germany February 1, 1928.

When in coin-released weighing machines equipped with means for delivering weight-indicating tickets all the mechanisms for performing all the necessary operations are provided, such as the mechanisms for coupling the drive with the weighing mechanism by means of the coin, for preventing incorrect operation of the gears, for feeding the web of tickets, for releasing and operating the printing mechanism, for severing the printed ticket from the web, for locking the type carrier, and other sub-mechanisms, the construction was necessarily very complicated. Moreover there was experienced the drawback that the co-operation of the several mechanisms was inadequate and unreliable. The object of the present invention is to provide an exceedingly simple construction, incorporating all the necessary mechanisms for the operations recited above, while nevertheless ensuring efficiency of all the said mechanisms and reliability of operation in using the weighing machine.

An essential feature of the invention consists in combining the known slide operated by hand and coupled to the driving device by a coin with a slide moving transversely thereto by which second slide the printing of the ticket is effected. The printing slide which produces the impression by impact, is for this purpose subjected to the action of a spring and is moved into the position in which the spring is stressed by the first named slide. In this position the printing slide is locked by a detent, which only releases this slide after the first slide has completed its movement thus allowing the second slide to shoot forward and produce an impression on the ticket web by impact.

The combining of the known coin-operated slide with the printing slide movable transversely thereto and brought into the cocked position and finally released permits of such an arrangement of the ticket web feed and also of the drive for the same and other devices as will secure correct operation in a particularly simple and effective manner.

Fig. 1 of the accompanying drawing is a side elevation of the weighing machine, 50 and

Fig. 2 an end view of the same.

Figs. 3 to 6 are detail views to a larger scale.

When the hand lever 1, shown broken away

in Fig. 1 and in dotted lines in Fig. 2, is 55 depressed, the cam 2 connected therewith presses downwardly the small slide 3 which is slidably mounted on the vertical frame plate 4 by the guide 4^a and held normally in its upper position by the helical springs 3^a. By a coin 6 inserted into the coin slot or coin control 5 the movement of the slide 3 is transmitted in known manner to the U-shaped slide 7, which is slidable below the slide 3 on the frame plate 4 and guided 65 by the guide 8. In moving downward the slide 7 depresses a bar 9 slidable in fixed guides 9^a in opposition to the stress of a helical spring 9^b, Fig. 4, operating a crank arm 10 having a pawl 11 by the aid of a 70 lateral projection 9^d. By the downward movement of the bar 9 the ratchet wheel 12 and the shaft 12^a are rotated for a quarter of a revolution and by a helical return spring 12^c the crank arm and the pawl are 75 returned to initial position, when the bar 9 moves upwardly again. To ensure that the ratchet wheel shaft 12^a will be rotated exactly one quarter of a revolution there is mounted on the shaft 12^a a disc 13 having 80 four detent notches, Fig. 5. A locking bar 14 guided vertically above said disk 13 is raised in the upper position of the slide 7 to such an extent that the lower end thereof cannot engage a notch of the disk 13 at 85 the time it is in line therewith below it. When the slide 7 is moved downwards, the locking bar 14 is yieldingly depressed by a helical spring 14^a to permit engagement thereof with a notch after completion of a 90 quarter turn of the shaft 12^a, thus locking the shaft. On this shaft is mounted a feed roll 16 adapted to feed the web 15. Owing to the exactness of the quarter turn of the ratchet wheel shaft 12^a the web 15 will be 95 fed a uniform distance and therefore the tickets on which the weight is printed will always be of the same length when severed. To prevent premature or unnecessary unwinding of the web 15 means is provided to lock 100 the bar 9 when moved downwards to an insufficient extent. With this object in view the bar 9 is provided at its lower end with a series of teeth 9^c with which a detent 17 is adapted to engage to hold the bar 9 at 105 rest when the downward movement is interrupted. At the end of a weighing operation the detent 17 is disengaged.

The U-shaped slide 7 is connected at the lower ends of its limbs with two rods 18, the left one of which, Fig. 1, has a cam 18^a, Figs. 1 and 6, adapted to press a bifurcated brake-lever 19 away from the type-wheel 20. This brake-lever 19 is adapted to compel the type-wheel 20 to make an impression on the ticket. The type-carrier or type-wheel 20 is adjusted by the usual draw-bar 40 connected with the two weighing springs 41 and acted upon from the platform by the aid of a rack 42 and a pinion 43 mounted on the shaft 20^a of the type-wheel 20. To prevent the type-wheel when adjusted from rotating when the weighing operation is effected, it is held fast by the brake-lever 19. When the cam or wedge portion 18^a of the rod 18 has released the brake lever, its brake block is pressed against the type-wheel by a helical spring.

Below the U-shaped slide 7 on a transverse carrier attached to the vertical frame plate is mounted a third slide 22 slidable transversely to the movement of the slide 7, Fig. 7. The slide 22 is acted upon by two helical springs 23 and by cams 18^b on the two rods 18, Fig. 2. These cams which act upon rollers 32 mounted on the printing slide 22 exercise pressure in the upper position of the slide 7 upon the printing slide 22 towards the right, Fig. 2, thus stressing the springs 23. In this position also the printing slide 22 is locked by the spring-pressed detent 21, the lower end of which is bent upwardly to engage an opening 22^a in the slide 22. Shortly before the slide 7 finishes its downward movement a projection 21^a on the inside of one of its limbs presses the detent 21 downwards. Since at that time the cams 18^b of the bar 18 are in their lowest position and thus out of the way of the printing slide 22 the latter is permitted to shoot forward under the action of the springs 23. A pressure piece or head 24 mounted on the slide 22 then presses the web 15 against the type-wheel which is already properly positioned, an inking ribbon being interposed between the type-wheel and the web. At the same time as the printing slide shoots forward, a knife 25 severs the web. The ticket thus printed and severed is held in position by the pressure head 24.

The printing slide 22 is provided above the pressure head and with a date stamp 26, which is also brought close up to the web 15 and inking ribbon when the slide 22 shoots forward. A hammer 27 held yieldingly on the other side of the web by two helical springs 27^a is struck against the web by the slide to print the date on the web.

When the slide 7 is moved into its lowest position by the hand lever 1, it will be held in position by the double armed lever 28 which engages a shoulder 7^a on the slide by the end of its lower arm acted upon by the spring 28^a, while the bent end of its other

arm is in the path of an arm 29 on the shaft of the hand lever 1. When the latter is released the slide 3 at once moves upward under the action of the springs 3^a, allowing the coin 6 to drop down, and thereupon also moves the hand-lever further upwardly, the arm 29 effecting rotation of the lever 28, so that it releases the slide 7. The slide 7 is then also moved upwardly by the two springs 30 and the cams 18^b of the two rods 18 effect the return movement of the printing slide 22. At the commencement of the upward movement of the slide 7 the detent 21 is released and permitted to be drawn upwardly by its spring 21^c and engages with its upwardly bent end the opening 22^a of the printing slide 22. Since the detent 17 is mounted on the printing slide 22 it is brought back into the range of the teeth of the bar 9, thus again rendering idle any incomplete movements of the bar 9.

On the return movement of the printing slide a pawl 31 effects the forward movement of the two inking ribbons.

I claim:—

1. In a weighing machine of the type having provision for giving out weight-indicating tickets and incorporating a spring-pressed slide or the like operated by a hand-lever and an inserted coin, in combination, a spring-pressed printing slide adapted to move transversely to the first-named slide, a slidable bar having a cam surface arranged to move the printing slide into cocked position when operated upon by the first-named slide, and a detent adapted to hold the printing slide in said cocked position and to release the printing slide at the end of the movement of the first named slide, thus permitting the printing slide to shoot forward and to effect the impression.

2. A weighing machine according to claim 1, characterized in that the printing slide is provided with a pressure head arranged to strike laterally against the type-carrier when the printing slide shoots forwardly and to press the type-carrier against a web to effect an impression.

3. A weighing machine according to claim 1, characterized in that the printing slide is provided with a pressure head, a type-carrier adapted to be adjusted to the weight, the said pressure head being arranged to strike laterally against the type carrier on the printing slide shooting forwardly and to press the type-carrier against a web to effect an impression, and a knife arranged above the printing point and adapted to sever the web when the printing slide shoots forward.

4. A weighing machine according to claim 1, characterized in that the printing slide is provided with a pressure head, a type-carrier adapted to be adjusted to the weight, the said pressure head being arranged to strike laterally against the type-carrier when the printing slide shoots forward and to press the

type-carrier against a web to effect an impression, a date stamp adapted to approach the web when the printing slide shoots forward and a hammer adapted to strike against 5 said date stamp.

5. A weighing machine according to claim 1, comprising a bar having locking teeth by which the bar is arrested if the forwardly moving slide is moved to an insufficient degree.

6. A weighing machine according to claim 1, comprising a hand lever and a detent lever, the latter adapted to hold the first named slide when moved to its end position and to 15 be moved into its normal position by the hand lever on its return movement, in such manner that the slide is released.

7. A weighing machine according to claim 1, characterized by a bar carried by a slide, 20 and a brake lever normally held in operative position by said bar, and adapted, on being released from said bar by the slide moving

forwardly, to bear against the type-carrier to hold it against movement.

8. A weighing machine according to claim 1, comprising a feed roll, a ratchet wheel, a notched disk, a shaft on which said feed roll, said ratchet wheel and said disk are mounted, a slide-bar, a spring pressed locking bar, guides for said slide-bar and said locking bar, the slide-bar being movable downwardly by the first named slide, a crank and a pawl adapted to engage said ratchet wheel by the aid of said crank to effect partial rotation of the said feed roll when the locking bar 35 positioned above the disk is released by the movement of the first-named slide, so that said locking bar being spring pressed engages a notch in the disk and limits the predetermined partial rotation of the feed roll. 40

In testimony whereof I have signed my name to this specification.

ROBERT CHRISTOPH FREDERIK VOGEL.
